UNITED STATES PATENT OFFICE.

WILLIAM C. MATTERN AND WILLIAM KOCH, OF BROOKLYN, NEW YORK.

SASH-FASTENER.

1,103,214.

Specification of Letters Patent. Patented July 14, 1914.

Application filed January 29, 1913. Serial No. 744,961.

To all whom it may concern:

Be it known that we, WILLIAM C. MATTERN and WILLIAM KOCH, citizens of the United States, residing at Brooklyn, in the county of Queens and State of New York, have invented certain new and useful Improvements in Sash-Fasteners, of which the following is a specification, reference being had to the accompanying drawings.

10 This invention relates to new and useful improvements in window constructions and particularly to sash holders.

The invention has for its primary object a simple, durable and efficient construction of 15 sash holding device which may be easily manipulated to hold the sashes in various adjusted positions.

With this and other objects in view, the invention consists in certain constructions, 20 arrangements and combinations of the parts that we shall hereinafter fully describe and claim.

For a full understanding of the invention, reference is to be had to the following description and accompanying drawing, in 25 which,

Figure 1 is a vertical transverse sectional view thereof. Fig. 2 is an enlarged detail 30 sectional view showing the holder, and Fig. 3 is a fragmentary view of a part hereinafter specifically described.

In describing our invention, we shall refer to the drawing in which similar reference characters designate corresponding parts 35 throughout the several views and in which—

1 indicates a wall of a structure having a stationary window-frame 2 formed therein and movably mounted in this frame is an auxiliary frame 7, the latter frame being 40 preferably hinged to the stationary frame. The sill 4 of the frame 2 and the lower sill 8 of the auxiliary frame 7 are offset coincident with one another to provide abutting shoulders, whereby to limit the outward 45 movement of the auxiliary frame in the stationary frame, as clearly shown in Fig. 1 of the drawing. Slidably mounted in the auxiliary or secondary frame 7, are the upper and lower sashes 9 and 10, respectively, and our invention primarily contemplates the provision of means to retain these sashes in their various adjusted positions in the auxiliary frame.

In the side rails or stiles of the secondary 55 frame 7 are counter-sunk the bars 11, the

front faces of which are substantially corrugated or otherwise similarly serrated to provide the spaced concave recesses 12. Counter-sunk in the outer faces of each of the stiles of each sash is a metallic frame 13, 60 which has an outer plate-like member 14 formed thereon. This plate-like member 14 is provided with a slot 15 through which a locking bolt 16 is adapted to project, the outer end of this locking bolt is convexly designed as shown at 17 and a rack 18 is formed on the upper edge of this bolt. A pair of parallel arms 19 are formed on the bolt which project through openings in a wall of the frame and encircling these arms 70 between the last mentioned wall and the head of the bolt are the coil springs 20, which normally force said bolt to its extended position. Rotatably mounted in said frame 13 is a pinion or the like 21, the teeth 75 of which are disposed in mesh with the teeth of the rack 18, whereby when said bolt is moved in the frame, said pinion will be rotated.

Mounted in the upper portion of the frame 80 13 to move vertically therein, is a locking pawl or stud 22, the head of which is somewhat conical in design and adapted for engagement with the teeth of the pinion 21. A shank 23 extending upwardly from the head 85 22 is guided through an opening in a wall of the upper portion of the frame and encircling this shank between the last mentioned wall and the head 22 of this pawl, is a coil spring 24, which normally forces said 90 pawl downwardly into engagement with the teeth of the pinion 21. From this construction, it will be seen that the locking bolt 17 will be normally forced to its extended position to rest in engagement with the wall 95 of a cavity 12 and the same will be retained in this position through the locking of the pinion 21, the springs 20 and 24 being of sufficient strength to over-balance the weight of the sash proper. When force is 100 applied to the sash, however, the tension of these springs may be overcome and the sash may be raised or lowered, the particular shape of the head of the bolt and the shape of the recesses permitting said bolt to readily 105 ride over the spacing portions of the bar 11. It will be understood that as the bolt is forced inwardly, the pinion 21 will be caused to rotate, as the force will overcome the tension of the spring 24 and when the sash has 110

been raised or lowered to the desired point, it is obvious that the same will be automatically held in its adjusted position.

Extending horizontally of the auxiliary 5 or secondary frame 7 and mounted in the stiles thereof, is a flat bracing bar 25 and the meeting rails of the sashes 9 and 10 are grooved or offset from opposite edges thereof, to receive this bracing bar therein, as 10 clearly shown in Fig. 1 of the drawing. This bar should form a bracing and strengthening means for the secondary or auxiliary frame, when the latter is disposed beyond the main or stationary frame.

15 From the foregoing, it will be seen that we have provided a simple, inexpensive and efficient means for carrying out the objects of the invention and while we have particularly described the elements best adapted to 20 perform the functions set forth, it is obvious that various changes in form, proportion and in the minor details of construction may be resorted to without departing from the spirit or sacrificing any of the principles 25 of the invention.

Having thus described this invention, what we claim is:—

In a window construction, the combination with a frame, and a sliding sash suitably mounted therein; of a notched bar counter-sunk in a stile of said frame, a frame counter-sunk in a stile of said sash, a spring forced locking bolt carried in said frame and adapted to project therebeyond for engagement with said notched bar, the upper 30 edge of said bolt being provided with teeth, a pinion rotatably mounted in said last mentioned frame and meshing with the teeth on said bolt, and a spring forced locking pawl mounted in said frame and normally engaged with the teeth of said pinion. 35

In testimony whereof we hereunto affix our signatures in the presence of two witnesses.

WILLIAM C. MATTERN.
WILLIAM KOCH.
